O. WOODWARD,
TENSION REGULATING DEVICE FOR SPRINGS.
APPLICATION FILED JAN. 9, 1919.

1,388,230.

Patented Aug. 23, 1921.

UNITED STATES PATENT OFFICE.

OSCAR WOODWARD, OF BABYLON, NEW YORK, ASSIGNOR TO REMINGTON TYPE-WRITER COMPANY, OF ILION, NEW YORK, A CORPORATION OF NEW YORK.

TENSION-REGULATING DEVICE FOR SPRINGS.

1,388,230.

Specification of Letters Patent. Patented Aug. 23, 1921.

Application filed January 9, 1919. Serial No. 270,317.

To all whom it may concern:

Be it known that I, OSCAR WOODWARD, citizen of the United States, and resident of Babylon, in the county of Suffolk and State of New York, have invented certain new and useful Improvements in Tension-Regulating Devices for Springs, of which the following is a specification.

My present invention relates to tension regulating devices for springs, and its main object is to provide new and improved devices of the character specified.

To the above and other ends which will subsequently appear, my present invention consists in the features of construction, combinations of devices, and arrangements of parts hereinafter described and particularly pointed out in the claims.

In the accompanying drawings,

Figure 1 is a fragmentary perspective view of one form of my invention, said figure showing the tension regulating device and associate parts.

Fig. 2 is a horizontal sectional view, on an enlarged scale, taken on the plane indicated by the dotted line $\alpha\alpha$ in Fig. 1 and looking downward.

Fig. 3 is a view corresponding to Fig. 2 but showing different relationships of some of the parts.

Fig. 4 is a vertical sectional view, on an enlarged scale, taken on the plane indicated by the dotted line yy in Fig. 1 and looking in the direction of the arrow at said line.

Fig. 5 is a fragmentary vertical sectional view of a modification.

Referring to Figs. 1 to 4, 1 indicates a part capable of movement, in the present instance a dog rocker such as is found in the Remington typewriting machine. Said member or rocker 1 comprises a rock shaft 2 from which rises an upstanding arm or portion 3 near the middle, while from near the right-hand end there projects upward an arm 4. The ends of the rocker bear on horizontal screw pivots, the right-hand one of which is shown in the drawing and numbered 5, said pivot being adjustably secured in the lower end of a stationary part or lug 6. The member 1 is thus movably mounted or capable of movement, being operated or rocked backward by devices not shown but which may be controlled by finger keys, and thereafter may be returned or rocked forward to the normal position illustrated in

Fig. 1, this return movement being assisted by a restoring spring which in the present instance is a coiled spring 7 horizontally disposed and having its rear end connected to or hooked through a hole 4^a in the arm 4 of the member or rocker 1. The other or forward end of the spring 7 is connected to an adjustable stationary anchorage or tension regulating device to which my invention particularly relates.

My novel tension regulating device comprises generally two elements having a threaded engagement and hand controlled so that one of said elements to which the spring is connected may be moved either to stretch or relax the spring through an actuation of the other of said elements. More specifically, these elements comprise an angular threaded member or screw and a thumb nut mounted thereon. The threaded member, indicated as a whole by the numeral 8, comprises a body portion 9 that is screw threaded for the greater part of its length and an offset portion 10 which in this instance is bent from the forward end of the body portion and terminates in an eye 11 through which the forward end of the spring 7 is hooked, or the spring may be otherwise anchored or connected to the member 8. The body portion 9 is depressed and flattened at its outer or right-hand face, viewed from the front, as indicated at 12. This portion of the screw or threaded member passes through a hole or opening 13 formed in the lug 6, the diameter of said hole, which is not threaded, being large enough to permit the screw to pass back and forth. Engaging with the threaded portion 9 of the member 8 is a coöperating hand controlled member or thumb nut 14 comprising a neck 15, a knurled head 16 at the front end and a flange 17 at the rear end of the neck. This flange is preferably seated in a depression or counter-sink 18 in the front face of the lug 6 and is retained within said counter-sink by a stationary part or forked piece 19 which at its lower or forked end loosely embraces the neck 15 and is secured at its upper end by a screw 20 to the front face of the lug 6. The construction is such that the thumb nut may be turned or rotated freely by means of the knurled portion 16 but is held against lengthwise movement on the threaded member 8, the forked part 19 co-operating with the flange 17 to prevent such

movement forward, or toward the left in Fig. 2, and the bottom of the depression 18 preventing such movement toward the right. In order that the rotation of the thumb nut 14 may effect endwise movement of the threaded member 8, means are provided for preventing rotary movement of said threaded member without interfering with its longitudinal movement. Preferably said means 10 comprises a headed screw 21 which is threaded into the side of the lug 6 at the level of and at right angles to the hole 13, the screw 21 being turned in until its head contacts with the face of the lug, the shank of said 15 screw being of such length that at this time its inner end which is preferably flattened, extends into the depression 12 in the screw 8 but preferably not quite contacting with the bottom or flattened face of said depression 20 when said face is parallel with the flat end of the shank of the screw, as shown in Fig. 2. The construction is such that to and fro endwise movement of the screw 8 will be limited by the engagement of the 25 ends of the depression 12 with the sides of the screw 21, and consequently the maximum and minimum tension of the spring controlled.

The operation of the tension regulating 30 device will be briefly described. Assuming the parts are related as in Fig. 2 and that it is desired to strengthen the spring 7, or increase its tension, the operator turns the knurled finger piece 16 in clockwise direction, causing a rotary movement of the thumb nut 14. Since the thumb nut, as has 35 been explained, is held against any movement but one of rotation, the effect of this operation will be to move the member 8 longitudinally forward or toward the left in Fig. 2, the screw 21 preventing said member 8 from rotating. The result is that the anchorage proper or eye 11 is moved forward, or as in Fig. 2 leftward, and the 40 spring 7 is consequently stretched so that its tension is increased, the extent of increase of course depending on the extent of longitudinal movement of the member 8. In Fig. 3 the member 8 is shown at the limit 45 of its forward or leftward movement, this limit being determined by the engagement of the rear end or shoulder of the depression 12 with the side of the screw 21. If it is desired, on the other hand, to weaken the 50 spring 7 the thumb piece 14 is turned in the opposite direction, thus causing a longitudinal movement of the screw member 8 rearward, or toward the right in Figs. 2 and 3, and a consequent contraction and weakening 55 of the spring 7.

Changes may be made without departing from my invention. For example, instead of counter-sinking the front face of the lug 6 to form a seat, as at 18, which is partly 60 covered by the straight fork 19, the con-

struction may be modified as in Fig. 5. As there shown, the flange 17 abuts against the plane face of the lug 6 and is held from any substantial movement away from said face by a forked piece or part 22 which is 70 bent or offset forward to clear the flange 17 and loosely embrace at its lower forked end the neck portion 15 of the thumb nut 14. The fork 22 is secured in place against the lug 6 by a screw 20 which passes through 75 its upper end portion.

Other changes will suggest themselves to those skilled in the art. For instance, the screw 21 instead of being of a length such that it may be screwed in until arrested by 80 contact of its head with the side of the lug 6, may be somewhat longer so that it can be screwed in until its flattened point or end bears against the bottom of the depression 12 while the head of the screw remains out 85 of contact with the side of the lug. In this case it will of course be necessary to back off the screw slightly whenever it may be desired to adjust the spring because in normal position the screw will hold the member 90 8 against adjustment by a turning movement of the nut. After adjustment the screw may be turned in again to hold the member 8 in set position.

It will be seen that by my present invention I provide a simple but effective tension adjusting device which is readily controlled by hand and is capable of such nicety of adjustment that the spring tension may be varied to give the most advantageous results.

What I claim as new and desire to secure by Letters Patent, is:

1. The combination with a part capable of movement and a coiled spring connected thereto, of an adjustable anchorage for said spring comprising a screw to which one end of said spring is connected, a thumb nut mounted on said screw, a detachable stationary part coöperating with said thumb nut 11 to prevent it from moving along said screw, and means for holding said screw against rotary movement while permitting endwise movement thereof.

2. The combination with a part capable 11 of movement and a coiled spring connected thereto, of an adjustable anchorage for said spring comprising a screw to which one end of said spring is connected, a thumb nut mounted on said screw, a detachable stationary part coöperating with said thumb nut to prevent it from moving along said screw, and a set screw coöperative with a flattened depressed portion of said first recited screw to prevent rotary movement of said first recited screw to afford endwise movements thereof to an extent limited by the ends of said flattened depressed portion.

3. The combination with a rocker and a coiled spring having one of its ends con- 13

nected thereto, of an adjustable anchorage for said spring comprising an angular threaded member having an offset portion to which the opposite end of said coiled 5 spring is connected, a thumb nut mounted for rotation on the threaded portion of said member, a stationary fork partly embracing said thumb nut and assisting to prevent endwise movement thereof along said member, and a set screw coöperating with a flat-

tened depressed portion of said threaded member to prevent rotation while affording limited endwise movement thereof.

Signed at the borough of Manhattan, city of New York, in the county of New 15 York and State of New York, this 2nd day of January, A. D. 1919.

OSCAR WOODWARD.

Witness:

CHARLES E. SMITH.
